UNITED STATES PATENT OFFICE.

ARTHUR R. McARTHUR, OF GARY, INDIANA, ASSIGNOR TO AMERICAN SHEET AND TIN PLATE COMPANY, OF PITTSBURGH, PENNSYLVANIA, A CORPORATION OF NEW JERSEY.

SLITTING-SHEARS.

1,238,312.

Specification of Letters Patent. Patented Aug. 28, 1917.

Application filed July 31, 1915. Serial No. 41,084.

To all whom it may concern:

Be it known that I, ARTHUR R. McARTHUR, a citizen of the United States, residing at Gary, in the county of Lake and State 5 of Indiana, have invented certain new and useful Improvements in Slitting-Shears, described and claimed in the following specification.

My invention relates to apparatus used in 10 slitting long, wide and relatively thin metal sheets and plates into a plurality of long and narrow strips.

It is frequently necessary for manufacturers to cut rolled metal sheets and plates 15 into a series of narrow strips. To cut such strips with a reciprocating shear is slow and expensive, and cutting the sheets or plates in strips with rotary shears as heretofore constructed, has been unsatisfactory on account of difficulties encountered in feeding 20 the plates through the shears in a straight line, as is necessary to prevent the sheets or plates being cut on curved lines.

The primary object of my invention is to 25 provide a rotary slitting shear having improved means whereby the sheets of plates are slit into a plurality of rectangular strips of the same or of varying widths and having straight parallel edges.

Another object of the invention is to provide 30 a rotary slitting mechanism having the novel construction and arrangement of parts shown in the accompanying drawings, which is more fully described hereinafter and specifically pointed out in the appended claims.

Referring now to the drawings forming part of this specification, Figure 1 is a plan showing a slitting shear and feed mechanism constructed and arranged in accordance with 40 my invention.

Fig. 2 is a sectional side elevation of the same, the section being taken on the line II—II of Fig. 1, showing the gearing for actuating the slitting rolls and feed rollers.

Fig. 3 is a similar sectional side elevation, taken on the line III—III of Fig. 1, showing the arrangement of feeding rolls forming part of this invention, and the relative location of the slitting rolls and feed-out 45 rollers.

Fig. 4 is a sectional detail showing the construction of the adjustable slitting disks and the manner of locking these disks in ad-

justed position on the screw threaded slitting roll shafts.

In the accompanying drawings the numeral 2 designates slitting shear housings which have windows 3 for the slitting roll bearings, windows 4 for the feed-in roller bearings, and windows 5 for the feed-out 60 roller bearings. The housings, which are of the open top type, have housing caps 6, 6, mounted thereon, constructed and secured thereto in the usual known manner.

Adjustably secured in the windows 3 are 65 bearings 7 and 8, and rotatably mounted in these bearings are threaded shafts 9 and 10 on each of which a series of slitting disks or knives 11 and 12 are adjustably secured.

The disks 11 and 12 (as is shown in Fig. 70 4) are fastened to a collar 13 by means of a plurality of countersunk head screws 14, and the collars 13 are loosely mounted on the screw threaded shafts 9 and 10. Feather keys 15 secured in place on the collars by 75 means of a screw or bolt 16 project into the key ways 17 in the threaded shafts 9 and 10 to cause the slitting or cutting disks or knives 11 and 12 to rotate with the shafts.

The series of cutting disks 11 and 12, and 80 the collars 13 forming part thereof, are moved axially on the shafts 9 and 10 in adjusting the opposing disks or knives of each co-acting pair on the shafts 9 and 10 into cutting position relative to one another and 85 to adjust the adjacent pairs of knives to the required distance apart in cutting metal sheets into strips of the desired width, or series of widths.

A lock nut 18 is provided on the shafts 9 90 and 10 for the collar 13 of each disk, which serves to fasten the disks 10 and 11 in adjusted position on the shafts. The overlapping edges of each pair of cutting disks 11 95 and 12 prevent movement of these disks in one direction on the shafts 9 and 10, and the lock nuts 18 maintain the adjacent engaging sides of the pairs of cutting disks in cutting position.

Adjustably secured in the housing windows 4 are bearings 19 and 20 for the series of staggered feed-in rollers 21, 22, 23 and 24, 25, 26, and secured in the housing windows 5 are the bearings 27 and 28 for the pair of feed-out rollers 29 and 30.

The top bearings 19, 19, and 27, 27, for

the feed rollers, and the bearings 7 for the top slitting disk shaft 9, are suspended from the lower end of adjusting screws 31 which extend through screw threaded openings in the housing caps 6.

The disk shafts 9 and 10 are provided on one end with meshing spur pinions 32 and 33, the pinion 33 also meshing with the idler spur gears 34 and 35 which are rotatably mounted on pins or stub shafts 36 fixed on the side of one housing 2.

The feed-out rollers 29 and 30 are provided on one end with meshing spur pinions 37, 38, and the pinion 38 on the roller 30 meshes with and is driven by the idler spur gear 34.

The feed-in rollers are driven through the idler spur gear 35, a spur pinion 39 on one end of the roller 24 meshing with the idler spur gear 35.

On the opposite end of the roller 24 are the spur pinions 41 and 42. The pinion 41 meshes with a similar pinion 43 on the roller 21, and the pinion 42 meshes with a wide face pinion 44 on the end of the roller 22. The pinion 44 in turn meshes with the pinion 45 on the end of the roller 25.

On the opposite end of the feed roller 25 is a pinion 46 which meshes with the pinion 46^a on the adjacent end of the roller 23 and also secured on this end of the roller 23, on the outside of the housing 2, is a pinion 47 which is in mesh with and drives the pinion 48 secured on one end of the feed roller 26. It will thus be seen that all of the feed-in rollers are positively driven, through the medium of the just described gears, these gears having long teeth, which enables the slight amount of vertical adjustment of the top set of rollers 21, 22, and 23 toward and away from the bottom set 24, 25 and 26 being made.

The shaft 10 is provided with a spur gear 49 which meshes with a spur pinion 50 in the driving shaft 51 which is driven by means of a motor (not shown) of any approved type.

By reference to Fig. 3 it will be seen that the three rollers 21, 22 and 23 forming the top series of the feed-in rollers are staggered relative to the series of three bottom rollers 24, 25 and 26, so that the axes of these sets of rollers are in different vertical planes.

Heretofore, with such feed mechanism it has been the practice to use a pair of feed-in rollers in which the axis of the top roller is in alignment in the same vertical plane as the opposite lower roller. With this construction, the plates or sheets 52, in passing between the rollers, has a line contact with the rollers, and the rollers must be very carefully adjusted so as to equalize the pressure on the sheets or plates at all points in its width. Even with the most careful adjustment difficulty has been experienced in feed-

ing the plates into the slitting rolls in a straight line, and as a result the slitted strips are cut on curved lines instead of being cut in the desired parallel straight lines.

By staggering the rollers of the top series 70 with respect to the bottom series of rollers, as is shown in Fig. 3, the plates or sheets, in being fed to the slitting knives by these feed rollers, have a surface contact with the rolls so that the plates are positively fed 75 forwardly in straight lines, and sidewise slipping of the plates between the opposing plates of the feed-in rollers is avoided and overcome.

In the operation of my improved apparatus, the disks 11 and 12 on the opposite screw threaded shafts 9 and 10 are adjusted lengthwise on these shafts so that the cutting faces of the disks on one shaft are spaced at a distance apart which will form 85 a series of strips of the desired width, and the disks on the other shaft are in cutting engagement with the first series of disks, or as shown in Fig. 4. The lock nuts 18 are then adjusted on the screw threaded shafts 90 9 and 10 so as to secure the pairs of knives or cutting disks 11 and 12 in adjusted position thereon.

The adjusting screws 31 from which the top bearings 7 are suspended are then ad- 25 justed to cause the cutting disks 11 on the top shaft 9 to overlap the disks 12 on the lower shaft 10 to the necessary extent. The adjusting screws 31 from which the top feed-out roller 29 is suspended, and the pairs 100 of adjusting screws 21 from which the top series of feed-in rollers is suspended, are then adjusted to suit the gage or thickness of the sheets or plates to be slitted.

The sheet or plate 52 is then fed forwardly 105 by hand in the direction indicated to bring the front end thereof into engagement with the bite of the first of the series of feed-in rollers 23, 26. The plate is gripped and fed forwardly by these rollers into the bite of 110 the series of feed-in rollers and is engaged by these rollers so as to have a surface contact therewith on account of the reverse curves into which the plate is bent by the staggered feed-in rollers. The sheet or plate 115 is gradually fed forwardly into the bite of the slitting disks 11 and 12 and is cut or slitted into strips of the desired width.

The number of pairs of slitting disks 10 and 11 employed at any one time will de- 120 pend upon the width of the sheets or plates being operated upon, and the relative width of the strips into which the sheets are to be cut, the number of pairs of cutting disks being increased or lessened as is required 125 in each particular case.

The forward end of the slitted sheets or plates upon emerging from between the slitting disks 11 and 12 is engaged by the feed-out rolls 29 and 30, and the strips 130

are fed forwardly between these rolls at the same speed at which the plates are being slit into strips.

The above described operations are then repeated with the successive sheets or plates operated upon, the slitting rolls or disks being adjusted as is necessary, with a change in thickness or gage of the materials being cut, and the cutting disks being adjusted lengthwise on the screw threaded shafts as becomes necessary in making the strips of the desired width.

The advantages of my invention will be apparent to those skilled in the art. By employing a series of staggered feed-in rollers instead of a pair or series of pairs of rolls in which the axes of the top and bottom rollers of each pair are in the same vertical plane, the plates or sheets to be cut have a surface contact with the feed-in rollers instead of a line contact by causing surface contact between the sheets and rollers, and the difficulty of preventing cutting of the strips in a curved line instead of in the desired straight line is overcome. The feed-in rollers also act as flattening rollers to remove any buckles in the sheets or plates.

Modifications in the construction and arrangement of parts may be made without departing from my invention as defined in the appended claims. The threaded shafts for the slitting rolls may be replaced by unthreaded shafts, the number of cutting disks on the shafts may be varied, and other changes may be made.

I claim:—

1. Cutting mechanism for sheets and plates comprising cutting disks and means for feeding the sheets and plates into engagement with said disks, said feeding means having a surface contact with the sheets or plates, and means for actuating said disks and feeding means.

2. Slitting mechanism for sheets and plates comprising shearing mechanism having means for cutting the sheets and plates into strips, means for feeding a sheet or plate into cutting engagement therewith, and means for driving said shearing mechanism and feeding means, said means including a plurality of cylindrical feed rollers having a surface contact with the sheet or plate.

3. A slitting mechanism for sheets and plates comprising opposed shafts having a series of cutting disks thereon, means for adjusting said disks axially on said shafts, means for feeding a sheet or plate into engagement with said cutting disks, said means having a series of cylindrical feed rollers with the axes of the top series staggered relatively to the lower series of rollers, and means for operating said disks and feed rollers.

4. A slitting mechanism for sheets and plates comprising opposed shafts having a series of cutting disks thereon, means for adjusting said disks axially on said shafts, means for feeding a sheet or plate out of engagement with said cutting disks, means for feeding a sheet or plate into engagement with said cutting disks, said means having a series of cylindrical feed rollers with the axes of the top series staggered relatively to the lower series of rollers, and means for operating said disks and feed rollers.

5. A rotary shearing mechanism for sheets and plates comprising opposed shafts, cutting disks adjustably secured on said shafts, means on the shafts for securing said disks in adjusted position thereon, a feed mechanism for delivering the sheets and plates into cutting engagement with said cutting disks, said feed mechanism having a plurality of top and bottom feed rollers, with the axes of the top rollers out of alinement with the axes of the bottom rollers in a vertical plane, and means for actuating said feed rollers.

6. A rotary shearing mechanism for sheets and plates comprising opposed shafts, cutting disks adjustably secured on said shafts, means on the shafts for securing said disks in adjusted position thereon, a feed mechanism for delivering the sheets and plates into cutting engagement with said cutting disks, said feed mechanism having a plurality of cylindrical top and bottom feed rollers, with the axes of the top rollers out of alinement with the axes of the bottom rollers in a vertical plane, means for adjusting one set of rollers relative to the other, and means for actuating said feed rollers.

7. A rotary shearing mechanism for sheets and plates comprising opposed shafts, cutting disks adjustably secured on said shafts, means on the shafts for securing said disks in adjusted position thereon, a feed mechanism for delivering the sheets and plates into cutting engagement with said cutting disks, said feed mechanism having a plurality of cylindrical top and bottom feed rollers, with the axes of the top rollers out of alinement with the axes of the bottom rollers in a vertical plane, means for adjusting the rollers of one set vertically relative to the other, and means for actuating said feed rollers.

8. A rotary shearing mechanism for sheets and plates comprising opposed threaded shafts, cutting disks adjustably secured on said shafts, means on the shafts for securing said disks in adjusted position thereon, a feed mechanism for delivering the sheets and plates into cutting engagement with said cutting disks, said feed mechanism having a plurality of cylindrical top and bottom feed rollers, with the axes of the top rollers out of alinement with the axes of the bottom rollers in a vertical plane, means for adjusting the rollers of one set vertically relative to the other, and means for actuating said feed rollers.

- axes of the bottom rollers in a vertical plane, means for adjusting the top set of rollers vertically relative to the bottom set, and means for actuating said feed rollers.
- 5 9. Apparatus for slitting sheets and plates comprising slitting rolls having a plurality of pairs of slitting disks, and means for mechanically feeding the plates into engagement with said slitting rolls, said
- 10 means comprising staggered cylindrical feed rollers arranged to have a surface contact with the plates or sheets in the plate or sheet feeding operation.
10. Apparatus for slitting sheets and plates comprising slitting rolls having a plurality of sets of slitting disks thereon, and a feed mechanism for mechanically feeding the sheets and plates into cutting engagement with said slitting rolls, said feed mechanism having a sinuous path for the sheets and plates to thereby prevent sidewise movement of said sheets and plates in the slitting operations.
- 15 11. Apparatus for slitting sheets and plates comprising slitting rolls having a plurality of sets of slitting disks thereon,
- 20
- 25
- and a feed mechanism for mechanically feeding the sheets and plates into cutting engagement with said slitting rolls, said feeding mechanism comprising staggered feed rolls arranged to form a sinuous path therebetween for the sheets and plates and thereby prevent sidewise movement of the sheets and plates in the slitting operations.
12. Apparatus for slitting sheets and plates comprising slitting rolls having a plurality of sets of slitting disks thereon, and a feed mechanism for mechanically feeding the sheets and plates into cutting engagement with said slitting rolls, said feeding mechanism comprising staggered feed rollers arranged to bend the uncut portions of the sheets and plates into reverse curves to thereby prevent sidewise movement of the sheets and plates in the slitting operations.

I, testimony whereof, I have hereunto set my hand.

ARTHUR R. McARTHUR.
